HEAT EXCHANGER

Frank M. Bennett, Canton, Ohio

Application June 27, 1946, Serial No. 679,782

5 Claims. (Cl. 257—240)

1

The invention relates to a heat exchanger, and more particularly to a device of this character which is adapted for heating or cooling fluids which are passed therethrough.

It is an object of the invention to provide a heat exchanger comprising a fin coil inserted in a light sheet metal container which in turn is located within an outer shell or container, fluid to be heated or cooled being passed through the outer and inner containers and around the fin coils through which the heating or cooling medium is passed.

Another object is to provide a heat exchanger of this character in which the fin coils are provided with baffles on opposite sides and in staggered relation, spaced so as to direct the flow of the fluid being heated or cooled back and forth through the fins at the velocity necessary for the desired rate of heat transmission.

A further object is to provide such a heat exchanger in which the inlet to the inner container is restricted so that there is more pressure in the outer shell than in the inner container, whereby this pressure holds the four sides of the inner container tightly against the edges of the fins and baffles causing the fluid to take a zig-zag or tortuous path through the fins and around the coils to the outlet.

A still further object is to provide a heat exchanger of the character referred to in which the baffles are in the form of metal sheets folded upon themselves and located over the edge portions of certain of the fins, the inner edges of the baffles contacting the coils and the outer edges thereof contacting the walls of the inner shell.

The above objects together with others which will be apparent from the drawings and following description, or which may be later referred to, may be attained by constructing the improved heat exchanger in the manner hereinafter described in detail and illustrated in the accompanying drawings, in which:

Figure 1 is a plan sectional view through a heat exchanger embodying the invention;

Fig. 2 a fragmentary, vertical sectional view of the inlet end portion of the heat exchanger;

Fig. 3 a transverse sectional view taken as on the line 3—3, Fig. 1; and

Fig. 4 an enlarged detached fragmentary perspective view of a portion of one of the baffles.

The heat exchanger is housed within an outer shell or container indicated generally at 10 which may be of cylindrical shape as shown in the drawings having a head 11 welded or otherwise fixed at the outlet end and provided with the

2

outlet opening 12 and the outlet neck 13 which may be internally screw threaded as at 14 to receive a discharge pipe for conveying the heated or cooled fluid to any suitable place.

5 A flange ring 15 may be welded or otherwise fixed to the other end of the cylindrical shell 10 for connection to the head 16 as by the bolts 17, a gasket 18 being located between the flange ring 15 and the head 16 to provide a fluid tight joint.

An inner shell or container 19, preferably of rectangular cross sectional shape, is located within the outer shell 10, the corners of the inner shell being tacked or otherwise attached to the inner wall of the cylindrical outer shell 10 in such manner that fluid may pass around the corners of the inner shell so as to entirely fill the space between the inner and outer shells.

This inner shell 19 is formed of thin sheet metal and is connected at one end to the head 11 by means of the angular sheet metal strips 20 which may be attached to the shell 19 and the head 11 by welding, soldering or other suitable means.

15 20 25 The other end of the inner shell 19 is closed by the end wall 21 having the flanges 22 around its edges which may have a sliding fit within the adjacent end of the shell 19.

An inlet 23 is provided at the opposite end of the outer shell 10 from the outlet 12 and may be internally threaded as at 24 for the connection of a pipe leading from any suitable source of supply of the fluid to be heated or cooled. Adjacent to the inlet 23 a restricted inlet orifice 25 is formed in the inner shell 19.

30 35 40 A plurality of coils 26, of copper tubing or the like, are located throughout the interior of the inner shell or container 19, the ends 27 and 28 of the tube being located through the head 16 and connected to any suitable source of heating or cooling medium, all of the coils 26 being spaced inwardly from the walls of the inner shell or container 19, as shown in the drawings.

Fins 29 are mounted in spaced relation upon the coils 26 each fin being a rectangular sheet of metal of such height as to snugly fit within the inner shell 19 and of a length considerably less than the width of the inner shell so that the side edges 30 of the fins are spaced a considerable distance from the side walls of the inner shell.

45 50 For the purpose of providing a tortuous or zig zag path through the fins and around the coils, baffles are mounted upon certain of the fins at spaced points and oppositely staggered.

Each of these baffles may be formed of a sheet of metal folded upon itself as indicated at 31, being of such width that when fitted over the edge of a fin as shown in Figs. 1 and 3, the inner open edges of the baffle will contact the coils, as indicated at 34, and the outer closed edge of the baffle will contact the adjacent side wall of the inner shell 19, while the baffle is of such height that the upper and lower ends thereof will contact the upper and lower walls of the inner shell 19.

A refrigerant or other cooling medium, or any suitable heating medium, is passed through the coils 26 depending upon whether it is desired to cool or heat fluid passed through the heat exchanger.

Fluid to be heated or cooled is admitted through the inlet 23 filling the space between the inner and outer shells and passing through the restricted orifice 25 to the inner shell, filling the same.

The inlet orifice 25 to the inner shell being considerably smaller than the inlet 23 to the outer shell produces considerably more pressure within the outer shell than in the inner shell, flexing the thin sheet metal walls of the inner shell 19 inward holding the four walls of the inner shell tightly against the edges of the fins and baffles so that the fluid is required to take a zig zag or tortuous path back and forth through the fins and around the coils in order to reach the outlet 12, so as to increase the heat exchanging capacity of the device.

If a cooling medium is passed through the coils 26, the multiplicity of fins 29 will be cooled thereby and as the fluid passes back and forth through the fins and around the coils, the cooled fins will absorb heat from the fluid so that it will be considerably cooled until it reaches the outlet 12.

On the other hand if a heating medium is passed through the coils 26, the multiplicity of fins will be rapidly heated by conduction and will give off this heat to the fluid passing through the inner container in a tortuous path so that the fluid will be considerably heated by the time it reaches the outlet 12.

I claim:

1. A heat exchanger comprising an outer cylindrical shell, an inner rectangular thin sheet metal shell located within the outer shell the corners of the inner shell being attached to the outer shell in such manner that fluid may pass around said corners so as to entirely fill the space between the inner and outer shells, a series of coils located through the inner shell, means for passing heating or cooling mediums through the coils, rectangular imperforate fins upon the coils, two opposite edges of the fins contacting the adjacent walls of the inner shell, the other two opposite edges of the fins being spaced from the adjacent walls of the inner shell, oppositely staggered baffles mounted upon certain of said last named edges of the fins and contacting the adjacent walls of the inner shell, inlet means near one end of the outer shell, an inlet opening to the inner shell adjacent thereto and being considerably smaller than the inlet to the outer shell and outlet means at the opposite end of the inner shell, whereby fluid passing through the inner shell is caused to travel in a tortuous path around the coils and through the fins from the inlet to the outlet.

2. A heat exchanger comprising an outer cylindrical shell, an inner rectangular thin sheet metal shell located within the outer shell the

corners of the inner shell being attached to the outer shell in such manner that fluid may pass around said corners so as to entirely fill the space between the inner and outer shells, a series of coils located through the inner shell, means for passing heating or cooling mediums through the coils, rectangular, imperforate fins upon the coils, two opposite edges of the fins contacting the adjacent walls of the inner shell, the other two opposite edges of the fins being spaced from the adjacent walls of the inner shell, oppositely staggered baffles mounted upon certain of said last named edges of the fins and contacting the adjacent walls of the inner shell, each of said baffles comprising a sheet of metal folded upon itself and receiving the adjacent edge portion of a fin in said fold, an inlet near one end of the outer shell, an inlet opening to the inner shell adjacent thereto and being considerably smaller than the inlet to the outer shell and outlet means at the opposite end of the inner shell, whereby fluid passing through the inner shell is caused to travel in a tortuous path around the coils and through the fins from the inlet to the outlet.

3. A heat exchanger comprising an outer cylindrical shell, an inner rectangular, thin sheet metal shell, located within the outer shell the corners of the inner shell being attached to the outer shell in such manner that fluid may pass around said corners so as to entirely fill the space between the inner and outer shells, a series of coils located through the inner shell, means for passing heating or cooling mediums through the coils, rectangular sheet metal fins upon the coils, the upper and lower edges of the fins contacting the top and bottom walls of the inner shell, the side edges of the fins being spaced from the side walls of the inner shell, oppositely staggered baffles upon the side edges of certain of the fins and contacting the adjacent side walls of the inner shell, a fluid inlet near one end of the outer shell, a restricted fluid inlet near the adjacent end of the inner shell and an outlet at the other end of the inner container, whereby fluid passing through the outer shell produces pressure upon the walls of the inner shell holding the same tightly against the edges of the fins and baffles so that the fluid passing through the inner shell is caused to travel in a tortuous path around the coils and through the fins from the inlet to the outlet of the inner shell.

4. A heat exchanger comprising an outer cylindrical shell, an inner rectangular, thin sheet metal shell, located within the outer shell the corners of the inner shell being attached to the outer shell in such manner that fluid may pass around said corners so as to entirely fill the space between the inner and outer shells, a series of coils located through the inner shell, means for passing heating or cooling mediums through the coils, rectangular sheet metal fins upon the coils, the upper and lower edges of the fins contacting the top and bottom walls of the inner shell, the side edges of the fins being spaced from the side walls of the inner shell, oppositely staggered baffles upon the side edges of certain of the fins and contacting the adjacent side walls of the inner shell, each of said baffles comprising a sheet of metal folded upon itself and receiving the adjacent edge portion of a fin in said fold, a fluid inlet near one end of the outer shell, a restricted fluid inlet near the adjacent end of the inner shell and an outlet at the other end of the inner container, whereby fluid passing through the outer shell produces pressure upon

the walls of the inner shell holding the same tightly against the edges of the fins and baffles so that the fluid passing through the inner shell is caused to travel in a tortuous path around the coils and through the fins from the inlet to the outlet of the inner shell.

5. A heat exchanger comprising an outer cylindrical shell, an inner rectangular, thin sheet metal shell, located within the outer shell the corners of the inner shell being attached to the outer shell in such manner that fluid may pass around said corners so as to entirely fill the space between the inner and outer shells, heads forming common end walls for both shells, a series of coils located through the inner shell, means for passing heating or cooling mediums through the coils, rectangular sheet metal fins upon the coils, the upper and lower edges of the fins contacting the top and bottom walls of the inner shell, the side edges of the fins being spaced from the side walls of the inner shell, oppositely staggered baffles upon the side edges of certain of the fins and contacting the adjacent side walls of the inner shell, each of said baffles comprising a sheet of metal folded upon itself and receiving the adjacent edge portion of a fin in said fold, a fluid inlet near one end of the outer shell, a

restricted fluid inlet near the adjacent end of the inner shell and an outlet at the other end of the inner container, whereby fluid passing through the outer shell produces pressure upon the walls of the inner shell holding the same tightly against the edges of the fins and baffles so that the fluid passing through the inner shell is caused to travel in a tortuous path around the coils and through the fins from the inlet to the outlet of the inner shell.
